UNITED STATES PATENT OFFICE.

ROBERT M. DICK, OF VANCOUVER, BRITISH COLUMBIA, CANADA.

FOOT MAT.

Application filed August 31, 1925. Serial No. 53,691.

This invention relates to a foot mat which is particularly designed to utilize the disused and rejected inner tubes of pneumatic tires.

5 These tubes are of pure rubber, the quality of which is not sensibly impaired when they are rejected for their inability to retain air under pressure, and as this rubber cannot be favourably regenerated and is 10 very durable in wear, I propose to cut them into bands about an inch wide and weave these bands on a wire mesh frame to form a mat.

The invention is fully described in the 15 following specification, reference being made to the drawings by which it is accompanied, in which:

Fig. 1 is a section of the mat showing the weave of the bands on the wire frame, and 20 Fig. 2 is a plan of the same.

Figure 3 is a cross section of the wire frame.

In these drawings 2 and 3 represent the longitudinal, and 4 the transverse wires of 25 the base frame on which the bands 5, cut from a disused pneumatic tire, are woven.

The wires may be crimped that they will cross one another and retain the spacing at the crossings.

30 It will be noted that the wires 2 are in pairs and relatively close together, with a single wire 3 between each pair of wires 2 and spaced apart from them about three times the pitch of two or approximately one 35 inch, and the transverse wires 4 come between each line of bands 5 as threaded on the wires 2, 3.

The bands 5 as cut from a rejected inner tube, are about one inch wide and, as shown 40 in Fig. 1, one end loop of the band is threaded on one of the wires 2 and thereafter passes doubled around the adjacent wire 3 on the same side and over the two wires 2 passes around the wire 3 on the opposite side, and 45 is looped on the other wire 2 of the pair.

These bands 5 are looped in the manner described on every alternate pair of wires 2 across the width of the frame and are staggered in relation to one another on the alternate rows, so that when finished the mat offers to the tread two thicknesses of the rubber over the single wires 3, and three thicknesses over each pair of double wires 2. It 50 thus forms a comfortable and very effective 55 mat with plenty of interspace between the

wiping pads for the dust and dirt removed from the boot or shoe to fall through.

It also forms a comfortable mat to stand on either for sink or washtub, as it does not absorb the water and is soft and elastic to 60 the feet.

The frictional hold it affords to the feet and its noiseless characteristics admirably adapt it for stair treads.

The wires 2, 3 should be pitched apart in 65 relation to the circumference of the bands 5 that they will be drawn tight over them without being stretched.

Having now particularly described my invention, I hereby declare that what I claim 70 as new and desire to be protected in by Letters Patent, is:

1. A mat consisting of a plurality of parallel longitudinal wires and transverse wires woven through the longitudinal wires, endless 75 rubber bands looped around certain groups of the longitudinal wires and secured to the inner wires of the group, said bands being arranged in parallel alternate series whereby to form a checker work of 80 rubber band pads and interspaces, said transverse wires extending transversely between the units comprising the alternate band series.

2. A mat consisting of a plurality of parallel longitudinal wires and parallel transverse wires, endless rubber bands looped around certain groups of the longitudinal wires and secured to the inner wires of the group, said bands being arranged in parallel alternate series whereby to form a 90 checker work of rubber band pads and interspaces, said transverse wires extending transversely between the units comprising the alternate band series, said wires being 95 crimped at the points where they cross each other to retain perfect spacing.

3. A mat comprising longitudinal and transverse woven wires, the longitudinal wires being arranged in groups of outer and inner pairs, and endless rubber bands looped around the outer pairs and secured to the inner pairs.

4. A mat comprising a plurality of wires arranged in sets of pairs one set consisting 105 of two adjacent wires and another set consisting of two separated wires, and endless rubber bands, the adjacent wires extending through the bands and the band being looped around the other wires of the set and 110

means for maintaining the adjacent and separated relation of the sets of wires.

5. A foot mat, comprising the combination with a frame of crossed longitudinal and transverse wires, of endless bands of sheet rubber looped around certain of the longitudinal wires and the other longitudinal wires being exposed to provide alternative parallel rows of pads and interspaces, a transverse wire being woven through the longitudinal wires between each pair of adjacent parallel rows of said pads.

6. A foot mat, comprising the combination with a frame work of crossed longitudinal and transverse wires, of a series of endless bands of sheet rubber, a loop of one end of each of which is threaded on a longitudinal wire and the doubled band carried around the adjacent longitudinal wire on

the same side and across to and over the longitudinal wire on the other side and around it and threaded on the longitudinal wire adjacent the one to which the other end is looped, the bands being arranged in adjacent rows staggered in relation to one another.

7. A foot mat, comprising the combination with a wire frame of crossed longitudinal and transverse wires, of a series of alternate rows of rubber pads each pad consisting of an endless band of sheet rubber which is passed over four longitudinal wires and the loop ends made fast to the two inner wires of the four, one transverse wire being positioned between the pads of adjacent rows.

In testimony whereof I affix my signature.

ROBERT M. DICK.
